HARRY R. LANGSLOW, OF ROCHESTER, NEW YORK.

TURNSTILE.

1,101,860.

Specification of Letters Patent. Patented June 30, 1914.

Application filed October 5, 1911, Serial No. 653,058. Renewed November 12, 1913. Serial No. 800,665.

To all whom it may concern:

Be it known that I, HARRY R. LANGSLOW, a citizen of the United States, and resident of Rochester, in the county of Monroe and 5 State of New York, have invented a certain new and useful Improvement in Turnstiles, of which the following is a full, clear, and exact description, reference being made to the accompanying drawings, forming part 10 of this specification.

This invention relates to improvements in turnstiles and in the railings or other barriers that coat therewith and form the passageways extending to and from them, the 15 object being to improve the form, construction and operation of the turnstiles so as to facilitate their manufacture, increase their efficiency and prolong their usefulness.

The invention consists of a combined turn- 20 stile and a barrier or barriers, the combined devices having such peculiarities of form, construction and arrangement as are described below and specified in the concluding claims.

25 On the accompanying sheet of drawings, which illustrate the invention in the form which is preferred for general use, and which consist of two views to which like reference-numerals are applied to designate 30 like parts in both views: Figure 1 is a plan of the apparatus; and Fig. 2, a side elevation thereof, the side shown being that indicated by the arrow below Fig. 1.

The turnstile shown comprises a rotary 35 post or pillar 1, whose upper part 2 forms a hub, and from this hub project five radial arms 3, these arms being affixed to the hub and spaced so that they are cut lengthwise by planes which contain the axis of the 40 pillar and form five angles of seventy-two degrees each.

The main railing or barrier comprises parts 4 and 5 which form an angle equal to two of the angles formed by the radial arms 45 of the turnstile, the arrangement of the angular barrier with respect to the turnstile being such that when the rotary part of the latter is in its normal position the outer end of one of its arms is close to the vertex 6 50 of the angle of the barrier, and the arms which are adjacent to the aforesaid arm are parallel to the parts 4 and 5 of the barrier. Other railings or barriers 7 and 8 extend close to the outer ends of the arms 3 which 55 are parallel to the parts 4 and 5 of the angular barrier, when the rotary part of the turn-

stile is in its normal position, the barriers 7 and 8 being parallel to the parts 4 and 5 respectively of the angular barrier.

It will be seen that an angular movement 60 of only seventy-two degrees is to be given to the arms 3 for each person passing the turnstile and walking in the passageways formed by it and the barriers described, and that five persons can pass the turnstile with 65 each full rotation of the rotary part there- 70 of. This renders it feasible to dispense with features of construction which turnstiles of the common or four-armed type contain, and whose main function is to insure an angular movement of ninety degrees by the arms each time a person passes such a turnstile, those features being in some cases springs and in others variously formed arms, which produce or aid in producing increments of 75 movement that impair rather than increase the efficiency of the turnstiles. Therefore, the manufacture of turnstiles is facilitated by this invention, and their efficiency is in- 80 creased so that five persons instead of four 85 can pass a turnstile with each rotation of the pillar on its axis, and without subjecting the apparatus to much if any greater wear and tear than a common turnstile gets when only four persons pass through it. 85

It will be understood that the invention might be embodied in combined turnstiles and barriers differing in form from those above described, such for example as turn- 90 stiles having more than five arms and bar- 95 riers adapted to coat therewith, and form suitable passageways leading to and from them.

Having thus described my invention, what I claim as new and desire to secure by Let- 95 ters Patent, is:

1. A combined turnstile, angular barrier, and two other barriers, the turnstile comprising a central hub and five equally spaced radial arms affixed thereto, the angular barrier comprising parts which form an angle equal to two of the angles formed by the arms of the turnstile, and the two other barriers being parallel to said parts of the angular barrier, the outer end of one of 100 said arms being close to the vertex of the first-mentioned angle and the adjacent arms being parallel to the sides of this angle and the outer ends of these adjacent arms being close to said two other barriers when the 105 rotary part of the turnstile is in its normal position. 110

2. A combined turnstile, angular barrier, and two other barriers, the turnstile having at least five equally spaced radial arms, the angular barrier comprising parts which 5 form an angle equal to two of the angles formed by the arms of the turnstile, and the two other barriers being parallel to said parts of the angular barrier, the outer end of one of said arms being close to the vertex 10 of the first-mentioned angle and the adjacent arms being parallel to the sides of this angle and the outer ends of these adjacent arms being close to said two other barriers when the rotary part of the turnstile is in its normal 15 position.
3. A combined turnstile and angular barrier, the turnstile having at least five equally spaced radial arms, and the barrier comprising parts which form an angle equal to 20 two of the angles formed by the arms of the turnstile, the outer end of one of these arms being close to the vertex of the angle of the barrier and the adjacent arms being parallel to the sides of this angle when the 25 rotary part of the turnstile is in its normal position.
4. A combined turnstile and angular barrier, the turnstile comprising a central hub

and five equally spaced radial arms affixed thereto, and the barrier comprising parts which form an angle equal to two of the angles formed by the arms of the turnstile, the outer end of one of these arms being close to the vertex of the angle of the barrier and the adjacent arms being parallel to the sides of this angle when the rotary part of the turnstile is in its normal position. 30

5. A combined turnstile and angular barrier, the turnstile having at least five equally spaced radial arms, and the barrier comprising parts which form an angle whose vertex is close to the outer end of one of the arms of the turnstile when the rotary part thereof is in its normal position. 35

6. A combined turnstile and angular barrier, the turnstile comprising a central hub and five equally spaced radial arms affixed thereto, and the barrier comprising parts which form an angle whose vertex is close to the outer end of one of the arms of the turnstile when the rotary part thereof is in its normal position. 40
